UNITED STATES PATENT OFFICE.

GUNNAR MADVIG, OF OAKLAND, CALIFORNIA.

DESIGN FOR A METAL HOLDBACK FOR CURTAINS AND DRAPERIES.

Application filed March 13, 1928. Serial No. 25,828. Term of patent 3½ years.

To all whom it may concern:

Be it known that I, GUNNAR MADVIG, a subject of the King of Denmark and a resident of the city of Oakland, county of Alameda, State of California, have invented a new, original, and ornamental Design for a Metal Holdback for Curtains and Draperies, of which the following is a specification, reference being had to the accompanying drawings, forming part thereof.

Figure 1 is a plan view of the holdback illustrating my new design.

Figure 2 is a side view of the holdback.

I claim:

The ornamental design for a metal holdback for curtains and draperies substantially as shown.

GUNNAR MADVIG.
